(57) **CLAIM**

The ornamental design for a monocular, as shown and described.

DESCRIPTION

FIG. 1 is a rear perspective view of a monocular showing our new design in accordance with an embodiment of the invention;

FIG. 2 is a rear elevational view thereof;

FIG. 3 is a front elevational view thereof;

FIG. 4 is a right side elevational view thereof, the left side elevational view being a mirror image thereof;

FIG. 5 is a top plan view thereof; and,

FIG. 6 is a bottom plan view thereof.

Where utilized, phantom lining is for illustrative purposes only and is not intended to limit or form any part of the claimed design.
